DESIGN FOR A HOUSE BAR

William C. Pahlmann, New York, N. Y.

Application October 3, 1940, Serial No. 95,609

Term of patent 3½ years

To all whom it may concern:

Be it known that I, William C. Pahlmann, a citizen of the United States of America, residing in New York city, county of New York, and State of New York, have invented a new, original, and ornamental Design for a House Bar, of which the following is a specification, reference being had to the accompanying drawing, forming part thereof, wherein—

I claim:

The ornamental design for a house bar, substantially as shown.

WILLIAM C. PAHLMANN.
